UNITED STATES PATENT OFFICE.

SYLVESTER A. GUTMAN, OF FLINT, MICHIGAN.

CARBURETION MEANS.

Application filed June 5, 1925. Serial No. 35,083.

My invention relates to means for delivering carburetable substance, such as gasoline, into a carburetor device.

One of the objects of my invention is an efficient means for positively delivering a carburetable substance into a carburetor device.

Another object of my invention is an efficient means for delivering carburetable substance into a carburetor device by means of power either from the power of an engine associated with the carburetor device or from another source.

Another object of my invention is an efficient means for positively delivering carburetable substance into a carburetor device irrespective of whether the receptacle containing the carburetable substance is located or positioned above or below the carburetor device.

Another object of my invention is an efficient means for positively delivering carburetable substance into a carburetor device, and controlling the delivery of the substance.

Another object of my invention is an efficient means for positively delivering carburetable substance into a carburetor device and collecting the overflow from the carburetor device and returning it to the receptacle containing the carburetable substance to prevent loss of carburetable substance in case the delivery means delivers more substance to the carburetor device than necessary.

Another object of my invention is an efficient means for positively forcing a carburetable substance into a carburetor device primarily by power means and secondarily by manual means when the power means is not available or when the carburetor device is empty and the power device can not be started.

Another object of my invention is an efficient means for forcing a carburetable substance into a carburetor device by means of power residing in an engine associated with the carburetor device, and controlling or regulating the speed of the means which forces the substance into the carburetor device by means of the substance in the carburetor device.

Another object of my invention is an efficient means for forcing carburetable sub-

stance into a carburetor device by means of a power device operated by power of an engine associated with the carburetor device such as an air current from a cooling fan, the flow of the cooling water, the flow of the exhaust, or the crank shaft, or the cam shaft, or other moving member; or by a moving element of a vehicle upon which the carburetor device is mounted or carried.

In carburetor devices previously made, the carburetable substance was, usually, fed into the carburetor device by means of gravity. When the receptacle for the carburetable substance was positioned below the carburetor device, a vacuum tank was employed in some instances to elevate the substance sufficiently far to permit such gravity feed; in other instances an air pump was used to create a pressure in the receptacle to force the substance into the carburetor device.

The vacuum tank mentioned often fails to work and requires delicate adjustment when it fails. Such adjustment requires an expert and the engine positively stalls until the adjustment is properly made. This failure of the vacuum tank results in considerable inconvenience and loss.

The air pump mentioned is, usually, manually operated and requires constant attention and frequent manipulation. With such a pump the pressure in the receptacle varies and consequently the flow of the substance varies also.

The two disadvantages mentioned are two of the main sources of trouble and loss in the previous devices or means and methods of supplying carburetable substance into a carburetor device.

The present invention aims to eliminate all possible disadvantages as well as losses found in previous devices and to provide a better method and means for delivering a carburetable substance into a carburetor device.

It is distinctly understood that the present application does not include the method nor the means of such accessories as vacuum tanks or air pumps which really do not pump the carburetable substance directly but which create a vacuum or an air pressure in the receptacle containing the substance to move the same.

In the accompanying drawing I have il-

lustrated my invention diagrammatically in two embodiments to show the features essential to carry out my invention in different forms and in different combinations of elements.

5 In the accompanying drawing:—

Fig. 1 is a diagrammatic perspective view of a pump and carburetor device, embodying the features of my invention, and shows a 10 pump device actuated by an air current, as from a cooling fan for instance, and a portion of a carburetor device associated with the pump device in a certain manner or relation and located or positioned near the bottom 15 tom of the pump device.

Fig. 2 is a fragmental sectional view, on a larger scale, of the lower portion of the pump device of Fig. 1 and shows a certain valve arrangement for the pump device.

20 Fig. 3 is a diagrammatic perspective view of a pump and carburetor device, embodying the features of my invention, and shows a pump device actuated by a belt from some source of power and a carburetor device associated with the pump device in a certain manner or relation and located or positioned above the pump device.

Similar reference characters refer to similar parts.

30 Referring now to Figs. 1 and 2 of the drawing:—

Although any sort of pump device may be employed to carry out my invention, I have shown here a vertical reciprocating pump 35 having the cylinder A and the piston B reciprocable therein. Any usual or special sealing means may be provided to prevent leakage between the piston and the cylinder wall.

40 The cap C is secured to the lower end of the cylinder A by means of the screws 10 and is provided with the main port 11 in communication with the cylinder bore. The inlet port 12 is in communication with the port 11 and the ball-valve 13 is interposed 45 between the ports 11 and 12. The outlet port 14 is in communication with the cylinder bore above the valve 13 and the ball-valve 15 is disposed in the port 14.

50 When the piston B moves upward in the cylinder A, the suction created by this movement of the piston raises the valve 13 and draws substance into the cylinder A while the valve 15 closes the outlet port. When the piston B moves downward in the cylinder A, the substance previously drawn into the cylinder 55 seats the valve 13 and closes the port 12 while the valve 15 is moved from its seat and the substance passes from the cylinder into the carburetor D through the pipe 16.

The lower end of the pitman E has the eye 17 disposed between the ears 18 of the piston B and swivels on the pin 60 extending through the eye 17 and the ears 18.

60 The upper end of the pitman E has the eye

19 engaging an eccentric to be more fully described later.

The shaft F is journaled in the bearing 20 which is supported on the cylinder A. The eccentric 21 is provided on the front end of the shaft F and fits the eye 19 previously mentioned. The handle 22 is provided on the rear end of the shaft F. The wheel 23, in the present instance a plain friction wheel, is secured to the shaft F.

75 The shaft G is journaled in the bearing 24 which is supported on the cylinder A. The fan wheel 25 is secured to the front end of the shaft G and the friction wheel 26 is secured to the rear end of the shaft G 80 in alignment and in contact with the friction wheel 23.

85 In the present instance, the fan wheel 25 has the band 27 within the tubular housing 28 which is supported on the arm which supports the bearing 24.

The brake shoe 29 is mounted in the housing 28 with the upper end thereof adjacent to and radial with the band 27 and the lower end 30 thereof extending through a 90 boss on the housing 28.

95 The carburetor D is connected to the lower end of the cylinder A by means of the pipe 16 previously mentioned and the float 31 is hinged within the carburetor. The float 31 is provided with the stud 32 projecting through the cover of the carburetor.

100 One end of the lever 33 is hinged to the cylinder A by means of the pin 34 and the other end is provided with the boss 35 into which the adjusting screw 36 is threaded; the nut 37 locks the screw 36 in adjusted position. The lever 33, intermediate the ends thereof, contacts the end 30 of the 105 brake shoe 29.

110 The funnel 38 is provided to collect an air current and to direct the same into the housing 28 and consequently into the fan wheel 25.

As to operation:—

The device now under consideration is operated by an air current such as might be produced by the cooling fan of an engine for instance.

115 The funnel 38 collects the air current and directs the same into the housing 28 and against the fan wheel 25 and thereby rotates the same as is well known in the art.

Since the friction wheels 23 and 26 are in contact, the rotation of the fan wheel 25 120 and consequently the shaft G and the wheel 26 thereon rotates the wheel 23 and consequently the shaft F and the eccentric 21 thereon.

125 Since the eye 19 of the pitman E engages the eccentric 21, and the eye 17 of the pitman E is hinged to the piston B, the described rotation of the shaft F causes the pitman E to reciprocate and consequently reciprocates the piston B to perform the 130

pumping action previously described to draw substance from the receptacle H and deliver it into the carburetor D through the pipe 16.

- 5 When the carburetor D is filled to a desired degree, the float 31 rises to the position shown in Fig. 1 and the end of the stud 32 forces the outer end of the lever 33 upward and thereby also forces the 70
10 brake shoe 29 upward and against the band 27 to act as a brake and either retard or completely stop the rotation of the fan wheel and consequently of the entire pump device.

- 15 The point of either retarded rotation or complete stoppage of the fan wheel is adjustable by means of the screw 36 which is locked in adjusted position by the nut 37.

- As soon as the float 31 recedes or drops 20 below the normal level, the outer end of the lever 33 drops accordingly due to its own weight in the present instance and thereby also permits the brake shoe 29 to drop and thereby disengage the band 27 and thereby 25 by removes the brake action on the band and permits the fan wheel to rotate and consequently start the pumping operation which will continue until sufficient substance is pumped into the carburetor to elevate the 30 float to normal position at which stage the rotation of the fan wheel may be so acted upon by the brake shoe that the same is restarted to rotate just enough or just fast enough to keep the float at its normal level. 35 If, for any reason, this brake shoe does not work properly to keep the normal level in the carburetor, the brake shoe will be forced tightly against the band and the pumping stopped in case the pump was running too fast and the level in the carburetor rose too high and, reversely, when the level falls too low, the brake action is removed completely to permit the pump to work at full speed until the level in the 40 carburetor is up to normal again. 45

- A certain speed reduction is shown in Fig. 1 by the wheels 23 and 26. The speed ratio may be varied to suit different conditions such as available air current or different heights to which the substance must 50 be lifted for instance.

- When the carburetor is empty and an engine is dependent upon the carburetor and, therefore, can not be started with an empty 55 carburetor, and when the air current to operate the pump mechanism depends upon the engine, the shaft F is rotated by means of the crank handle 22 until a sufficient quantity of substance is pumped into the carburetor. After the engine is started, the pump mechanism takes care of keeping the carburetor filled; the handle 22 is provided for emergency only.

- 60 The level of the substance in the carburetor, or, or in other words the upward limit of

the travel of the float, can be adjusted by means of the adjusting screw 36 to apply the brake sooner or later in the up and down travel of the float.

In some instances, the brake mechanism 70 may fail to retard or stop the rotation of the fan wheel and thereby permit more substance to be pumped into the carburetor than is consumed by the engine, resulting in flooding or overflowing of the carburetor. 75 In order to conserve this overflowing substance and to prevent the loss thereof, I provide the overflow pipe 39 between the carburetor and the receptacle to return the surplus or overflowing substance to the receptacle H. 80

Referring now to Fig. 3 of the drawing.

In this illustration I have again shown a vertical reciprocating pump means having the cylinder I and the piston J reciprocable 85 therein and pumping the substance into a carburetor similar to that shown in Fig. 1. Any usual or special piston sealing means may also be employed in this illustration.

The cap K is similar to the cap C described in connection with Figs. 1 and 2 and the carburetor L is similar to the carburetor D and has the float 40 and the stud 41.

The pitman M is similar to the pitman E described in connection with Fig. 1 and is 95 hinged to the piston J similar to the hinge joint between the lower end of the pitman E and the upper end of the piston B previously described. The upper end of the pitman M has the eye 42 for the purpose appearing presently. 100

The shaft N is journaled in the bearing 43 which is supported on the cylinder I. The pulley 44 is secured to the rear end of the shaft N and the belt 45 engages the same 105 and is driven by some source of power such as the crank shaft or the cam shaft or other moving part of the engine or by a device operated by the exhaust of the engine or by movement of the cooling water thereof or 110 other expedient which can produce movement of the belt 45.

The crank handle 46 extends from the rear end of the shaft N for the same purpose as the handle 22 of Fig. 1. 115

The eccentric 47 is here journaled on the shaft N and is provided with the notch 48 in the outer end surface thereof; otherwise the eccentric 47 is similar to and performs the same function as the eccentric 21 of Fig. 120 1 and engages the eye 42 of the pitman M.

The clutch 49 is slidably mounted on the front end of the shaft N and is rotated therewith by means of the feather 50. The inner end surface of the clutch 49 is provided with 125 the tooth 51 adapted to the notch 48.

The middle portion of the lever O is fulcrumed on the cylinder I by means of the pin 52. The lower end of the lever O engages the clutch 49 and the upper end of the 130

lever O has the adjusting screw 53 and the lock nut 54 similar to the adjusting screw 36 of Fig. 1 previously described. The adjusting screw 53 engages or abuts the stud 41.

The operation of this combination of elements is similar to the operation of the elements of Fig. 1 previously described.

When the carburetor L is filled, the float 10 40, and consequently the stud 41, rise sufficiently to push the outer end of the lever O upwardly sufficiently far to rotate the same on the pin 52 sufficient to throw the tooth 51 out of engagement with the notch 15 48, thereby disengaging the power means from the eccentric until the float has descended or dropped sufficiently far to again throw the clutch 49 into engagement with the eccentric and thereby start the operation 20 of the pump mechanism.

The pump mechanism may be located anywhere in relation to the carburetor and to the receptacle for the carburetable substance. A study of any condition to be met 25 in any particular case should determine whether the pump mechanism should be placed below the receptacle and push the substance upward, or whether it should be placed or located up near the carburetor 30 and pull the substance upward, or whether it should be located between the receptacle and the carburetor (vertically) to pull the substance upward part way and to push it upward the rest of the way.

35 As previously stated, the embodiments of my invention illustrated and described are diagrammatic only. I am aware that various modifications may and can be made in the structure of the elements as well as in 40 the arrangements and combinations and associations thereof within the scope of the appended claims.

Having described my invention as embodied in the two illustrations shown, and 45 without limiting myself to the construction of the elements so shown and described as well as the arrangements and combinations and associations of these elements so illustrated and described,

50 I claim:—

1. In a carburetion means, a carburetor having a float, a pump connected with said carburetor, a rotatable wheel to operate said pump, and friction means operated by said float to vary the speed of said wheel.

2. In a carburetion means, a carburetor having a float, a pump connected with said carburetor, a rotatable wheel to operate said pump, and a brake shoe moved toward and 60 away from said wheel by the rise and fall of said float to vary the speed of rotation of said wheel.

3. In a carburetion means, a carburetor having a float, a pump connected with said carburetor, a fan wheel to operate said 65

pump by means of an air current, and means operated by said float to change the speed of said fan wheel.

4. In a carburetion means, a carburetor having a float, a pump connected with said carburetor, a fan wheel to operate said pump by means of an air current, and friction means operated by said float to change the speed of said fan wheel.

5. In a carburetion means, a carburetor 75 having a float, a pump connected with said carburetor, a fan wheel to operate said pump by means of an air current, a fulcrumed lever operated by said float, and means operated by said lever to frictionally 80 engage said fan wheel.

6. In a carburetion means, a carburetor having a float, a pump connected with said carburetor, a fan wheel to operate said pump by means of an air current, a housing 85 inclosing said fan wheel circumferentially, a fulcrumed lever operated by said float, and a brake shoe movably mounted in said housing and operated by said lever to contact said fan wheel and thereby change the speed 90 thereof.

7. In a carburetion means, a carburetor, a pump connected with said carburetor, said pump being operated by means of an air current device, and brake means operated by 95 the rise and fall of liquid in said carburetor and arranged to change the speed of said air current device.

8. In a carburetion means, a carburetor, a pump connected with said carburetor, said pump being operated by means of an air current device, and means for changing the speed of said air current device by the rise and fall of liquid in said carburetor and completely stopping said air current device 105 when the liquid in said carburetor rises above a certain limit.

9. In a carburetion means, a carburetor having a float, a pump connected with said carburetor, said pump being operated by 110 means of an air current device, a fulcrumed lever operated by the rise and fall of said float, and means operated by said lever to change the speed of said air current device.

10. In a carburetion means, a carburetor, 115 a float in said carburetor, a pump connected with said carburetor, a fulcrumed lever operatively connected with the operating mechanism of said pump, a screw threaded into said lever and contacting said float, the 120 threaded engagement between said screw and said lever constituting a means for adjusting the operation of said pump according to the position of said float, and a nut threaded to said screw to lock the same in 125 adjusted position.

11. In a carburetion means, a carburetor, a plunger pump connected to said carburetor, an air fan journaled in a definite relation to said pump, a pump shaft journaled 130

in a definite relation to said pump and to said air fan, operative connection between said air fan and said pump, an eccentric rotatable with said shaft, and a connecting rod having an eye encircling said eccentric and being hinged to the plunger of said pump.

12. In a carburetion means, a carburetor, a pump connected with said carburetor,

power means to operate said pump, and means between said carburetor and said power means to vary the speed of said power means as the liquid in said carburetor rises and falls and to completely stop said power means when the liquid in said carburetor reaches a certain height. ¹⁰ ¹⁵

SYLVESTER A. GUTMAN.
